PIPE FITTING

Courtland G. Newton, Chicago, Ill., assignor to
Horace S. Kehm

Application September 20, 1937, Serial No. 164,662

2 Claims. (Cl. 138—37)

The present invention relates in general to a pipe fitting and is more particularly concerned with a novel construction in a fitting of the type used in fluid heat transfer systems, either heating 5 or cooling, for the purpose of stratifying the flow of the system fluid.

In the past, fittings for this general purpose have been utilized in connection with heating and cooling systems employing a single looped main, 10 wherein each radiator or cooler is connected to the main by supply and return risers. The fittings placed respectively at the supply and return risers for the purpose of automatically shunting a portion of the fluid in the main through the 15 radiators or coolers, have been of different internal construction to individually function as "supply" and "return" fittings.

The "supply" fitting was so arranged that fluid entering the supply riser of the radiator or cooler 20 was taken from the upper part of the main in the case of heating systems and from the lower part of the main in the case of cooling systems. At the "return" fitting, the fluid which was shunted past the radiator of a heating system 25 was carried to the top of the main and the fluid returning from the radiator was returned to the bottom of the main. In the case of a cooling system, the "return" fitting operated to direct the shunt fluid to the bottom of the main and 30 the heated fluid from the cooler to the top of the main.

While the fittings heretofore supplied worked very satisfactorily, they were expensive to manufacture in that the different internal constructions of the "supply" and "return" fittings required separate molds and separate machining for the respective fittings.

The present invention contemplates an improved fitting construction wherein both the 40 "supply" and "return" fittings embody identical elements. In the present instance, however, these elements are so arranged that they may be assembled in different relation to produce a "supply" or "return" fitting, as desired, at the 45 factory, thus materially decreasing the cost of manufacture.

A further object of the invention is to provide an improved pipe fitting construction which utilizes an insert which may be initially selectively disposed in different positions, depending upon whether the fitting is to form a "return" or "supply" fitting, and thereafter securing the insert in selected position.

55 A further object of the invention is to provide, as an article of manufacture, an improved insert for use with fittings of the type described.

Other objects and features of the invention will more readily appear from the following detailed description taken in connection with the

accompanying drawing which illustrates a single embodiment thereof, and in which:

Figure 1 is a longitudinal sectional view through a fitting embodying the features of the present invention, showing the internal arrangement of parts whereby the fitting is adapted for use as a "return" fitting of a looped heating system;

Figure 2 is a similar view showing the interior arrangement of parts to adapt the fitting for 10 use as a "supply" fitting of a heating system;

Figure 3 is an end view of the fitting, looking toward the right end of the fitting shown in Figure 1; and

Figure 4 is a similar view looking toward the 15 right end of the fitting shown in Figure 2.

As shown on the drawing:

The fitting of the present invention comprises a shell-like body portion 10 which may be constructed of brass, cast iron or other suitable material which may be cast or otherwise formed to define a main longitudinally extending passageway 11. The main passageway is terminated at its ends to form main opposed openings 12 and 13, these openings being threaded, if desired, 20 for connection to inlet and outlet pipes as shown at 14 and 15 which may constitute sections of a looped heating or cooling system. Intermediate the opposed openings and surrounding the main passageway 11 is an intermediate chamber 16 of 25 slightly greater diameter than the main passageway. This chamber has communicating therewith a branch opening 17, which may be disposed laterally at an angle to the main passageway and may be likewise threaded for connection 30 to a branch pipe as indicated at 18.

It will be noted that the intermediate chamber 16 is disposed in eccentric relation to the center line of the main passageway 11 so that a greater portion of the chamber will be disposed at the 40 portion thereof lying adjacent the branch pipe connection.

Regardless of whether the pipe fitting body is to be utilized to form a "supply" or "return" fitting, the fitting body is of the same construction in either case.

At the juncture of the connection openings 12 and 13 respectively with the intermediate chamber 16, there is provided annular shoulders 19 and 20, the latter shoulder preferably being of 50 slightly less width than the former.

Both the return and supply fittings make use of an insert member 21, which is arranged to be selectively disposed within the fitting body in 55 different positions, depending upon whether the ultimate fitting is to be used as a supply or return fitting.

This insert is preferably of a metallic material which may be easily worked. In general this 60

- insert is of tubular construction and is provided with round end openings, one of these openings as shown at 22 being of greater diameter than the other opening which is shown at 23.
- 5 The end openings 22 and 23 of the insert are disposed in eccentric relation and have their peripheries common to a longitudinally extending element of the insert which is disposed in right-angled relation to the respective planes of the 10 end openings.
- Between the ends of the insert the wall on one side of the insert is tapered as shown at 24 to take care of the difference in size between the ends of the insert.
- 15 In assembling the fitting, the large end 22 of the insert is disposed in surface engagement, with the shoulder 19, whereas the opposite end of the insert is disposed so that a portion of its circumference will abut the shoulder 20. Since the end 20 23 of the insert is of less diameter than the internal diameter of the shoulder 20, it will be apparent that a crescent shaped passageway will be formed around this end of the insert into the intermediate chamber.
- 25 The exterior diameter of the large end 22 of the insert is such that this end will snugly fit against the shoulder 19, but the fit is not so tight as to prevent rotation of the insert. The insert is initially disposed in the position shown 30 within the housing and is rotated either to the position shown in Figure 1 to form a return fitting or the position shown in Figure 2 to form a supply fitting. The insert is then secured against removal by expanding the large end 22 thereof 35 so that it forcibly engages the associated shoulder.
- In the return fitting arrangement, it will be noted that the small end 23 of the insert is disposed toward the branch connection 18 and that direct communication between the branch opening 40 and the opening 13 is prevented at the top of the intermediate chamber. Fluid flowing from the branch connection 18 as shown by the arrow must pass to the bottom portion of the intermediate chamber where it may enter the pipe 15 through the crescent-shaped opening defined by 45 the end 23 of the insert and the adjacent shoulder 20, and since the fluid returning from the branch opening, in the case of a heating system would be cooled to a temperature less than that 50 which continues through the insert, the return fluid from the branch opening will be injected or directed to the bottom of the pipe 15, this being the normal position which the fluid would assume due to its cooler temperature.
- 55 In the case of the supply fitting, the operative position of the insert, for use in a heating system, would be as shown in Figure 2. In this case the small end of the insert is at the portion of the intermediate chamber which is disposed on 60 the opposite side of the branch opening. In this position, direct communication is established through a similarly formed crescent-shaped opening from the upper portion of main opening 13 to the intermediate chamber so that the hottest 65 portion of the fluid passing through an inlet pipe 25 would pass into the branch connection, and the coolest portion of the fluid would continue straight through the insert into the shunt or outlet pipe 14. The crescent-shaped opening in 70 the return fitting, it will be noted, is oppositely disposed to the crescent-shaped opening in the supply fitting.

It will be readily apparent that these fittings may with equal facility be utilized in a cooling system in which case the fitting as shown in Figure 1 becomes a supply fitting and the flow of fluid therethrough is reversed; and likewise, 5 the fitting arrangement shown in Figure 2 becomes a return fitting, when the flow of fluid therethrough is reversed.

From the foregoing description, it will be apparent that this invention provides a novel construction of pipe fitting which may be utilized in connection with either a heating or cooling system to effect stratification of the circulatory fluid; which utilizes the same parts irrespective of whether the fitting is to be for a "supply" or 15 "return" connection; in which the parts are selectively capable of being positioned and secured in the selected position, depending upon whether or not the ultimate fitting is to be for a "return" or "supply" connection; and which utilizes a 20 novel insert construction.

Now, it is of course to be understood that although I have described in detail a single embodiment of my invention, the invention is not to be thus limited but only insofar as defined 25 by the scope and spirit of the appended claims.

I claim as my invention:

1. A pipe fitting comprising a hollow body structure defining opposed main openings and an intermediately disposed branch opening, said body at said openings being arranged for pipe connections, an annular shoulder in the body in axial alignment with one of the main openings and inwardly spaced from the body portion at said one main opening, a separate tubular 35 insert having one of its ends initially rotatably supported by said shoulder, said end being expandable into pressure engagement with said shoulder for frictionally maintaining the insert against rotational movement, and a contracted 40 portion formed in the insert at its opposite end, said contracted portion extending toward the other main opening and being disposed in eccentric relation to its axis.

2. A pipe fitting having parts arranged to be assembled in different relation to form "supply" and "return" fittings for use in heating and cooling systems of the type where the circulatory fluid is maintained stratified; said fitting comprising a body structure having opposed axially aligned main openings and a branch opening, said openings being arranged for receiving pipe connections to said body, an intermediate chamber in said body in communication with said openings, annular spaced apart shoulders in said chamber respectively disposed adjacent the main openings and axially aligned therewith, a separate tubular insert within said body, one end of the insert being initially supported for rotational movement by one of said shoulders, the other end of the insert being radially offset relative to the first end and having a portion of its periphery in abutment with the other of said shoulders, whereby the tubular insert may be rotated to initially vary the offset direction, said 55 rotatably supported end being capable of expansion into pressure engagement with its associated shoulder to fixedly secure the insert in the selected initial position.
